UNITED STATES PATENT OFFICE

2,341,955

DISPLAY BOX

Peter P. Smith, Teaneck, N. J.

Application April 3, 1942, Serial No. 437,497

2 Claims. (Cl. 62—102)

My invention relates to improvements in display boxes, and more specifically to display boxes for cold beverages or food; and the objects of my improvement are, first, to provide a continuous cooling of the displayed articles; and second, to afford facilities to make the displayed articles appear as if they were in a snow flurry, thus producing a pleasing impression of coolness on the onlooker and tending to stimulate a desire to partake of the articles so displayed.

Other important objects and advantages of the invention will become apparent during the course of the following detailed description when read in conjunction with the accompanying drawing, which forms a part of this specification and in which—

Figure 1 is a vertical section of the entire device on the line 1—1 of Fig. 3; Fig. 2, a partial side elevation; and Fig. 3, a horizontal section on the line 3—3 of Fig. 1.

Similar numerals refer to similar parts throughout the several views.

In the instance shown, the displayed articles are beverages in bottles 1, displayed in a receptacle which has transparent walls 2, 3 and 4, and transparent top covers 5 and 6, so that the bottles can be seen from three sides as well as from above. A door 7 is attached to the back of the box to permit filling and replacing.

In the space between the walls 2 and 3 are flakes 8 of light, white material, for instance of paper. A strainer 9 is on the top and a strainer 10 on the bottom of the walls 2 and 3 to prevent the flakes 8 from escaping when air is blown through the space between the walls 2 and 3, as referred to hereinafter. A plurality of tubes 11 (four in the present instance) terminate below the strainer 10 to convey cold air into the space between the walls 2 and 3. The tubes 11 lead to a device adapted to create an alternating flow of air.

I prefer to carry out this feature of my invention in the following manner: In a casing 12 (Figs. 1 and 3), which is connected to a refrigerating chamber 15 by inlet tubes 14, turns a shaft 16 carrying a fan 17. A disk 18 secured to shaft 16 carries a pin 19 which engages a pinion 20. A rotating shutter 21 has apertures 22 adapted to open and to close alternately the terminals of the tubes 11 when the shutter 21 rotates. This shutter 21 is provided with internal teeth 23 for receiving those of the pinion 20. The shaft 16 may be driven by a belt passing round the pulley 29 or by other suitable means. The fan 17, when revolving, sucks cold

air from the refrigerating chamber 15 and presses the air toward the shutter 21, which by means of the pin 19, the pinion 20, and the internal teeth 23 is turned at a lower speed than the shaft 16, whereby it alternately opens and closes the tubes 11. In Figs. 1 and 3 the shutter 21 is shown in a position where one of the tubes 11 is closed while the other is open so that air can flow through the open tube 11, the strainer

10, the space between the walls 2 and 3, the strainer 9, into the space where the bottles are kept, and from there through the pipes 24 back to the refrigerating chamber 15. While air is blown through the space between the walls 2 and 3, the flakes 8 are blown upward toward the strainer 9, and as soon as the blowing of air is interrupted by the shutter 21, the flakes 8 fall down. This continuous movement of the snow-like flakes 8 creates the appearance of an imitation snow flurry.

The bottles 1 are preferably placed on a wire spacer rack 25, to provide sufficient space between the bottles to insure circulation of air.

The device can also be constructed without the walls 4 and without the top plate 6; however, I prefer to furnish my device with the walls 4 and the top plate 6 to provide a cold insulating area between the walls 3 and 4 and the plates 5 and 6.

While in the instance shown the refrigerating chamber 15 is directly below the display box, it will be obvious that the tubes 14 and 24 can be connected to a refrigerating chamber which is situated at some other, more or less distant place. In this case, my display box can be placed, for instance, on a counter and can be connected by tubes or hoses to a refrigerating chamber, which is used for other purposes, or to an ice cellar.

The speed of the electromotor (not shown) which drives the shaft 16 can be controlled by hand or automatically by any thermostatically controlled mechanism as indicated in Fig. 1 at 27. Such a mechanism can be adapted to cause the fan 17 to revolve at a high speed until the temperature in the display box reaches a low point, say 40 to 45 degrees, and then to slow down the speed so that it is just sufficient to maintain an imitation snow flurry.

The shaft 16 can also be driven by the same motor which drives the refrigeration machinery (not shown). However, in this case, the snow flurry would discontinue when a thermostat, controlling the refrigeration machinery, switches off this machinery. Therefore, I prefer to have the shaft 16 driven separately and to attach two

thermostats, namely one 27 for the motor driving the shaft 16 and a second thermostat 28 for the refrigeration machinery.

Further modifications will be apparent to those skilled in the art and it is desired, therefore, that my invention be limited only by the prior art and the scope of the appended claims.

Having thus described my invention, what I claim and desire to secure by Letters Patent in the United States is:

1. In a display box, the combination of transparent inner walls defining a chamber for holding articles to be displayed; with transparent outer walls in spaced relation to said inner walls; flakes between said outer and inner walls; strainners cooperating with said walls to prevent said flakes from leaving the space between said walls; means to cause circulation of cold air from a refrigerating chamber through the space between the outer and the inner transparent walls, to the space surrounded by said inner transparent walls, and back to the refrigerating

chamber; said means including an air moving device, a plurality of air passages connecting the space between said outer and inner transparent walls with said device, and a rotatable shutter 5 having an opening therein and movable to cause each passage in its turn to be opened while certain of the passages are closed; all substantially as set forth.

2. In a display box having multiple paned 10 transparent walls arranged in horizontal planes with flakes in the space between panels, the combination of strainners arranged at the upper and lower edges of the panels and adapted to permit the passing of air therethrough but to keep said 15 flakes in the spaces between panels, with a plurality of air passages connecting the spaces between panels to a refrigerating chamber, means for circulating the air in said refrigerating chamber through said air passages, and means to 20 open and to close said air passages alternately, substantially as described.

PETER P. SMITH.
